UNITED STATES PATENT OFFICE.

ALBERT W. SMITH, OF ST. LOUIS, MISSOURI.

BED.

Application filed January 10, 1923. Serial No. 611,696.

To all whom it may concern:

Be it known that I, ALBERT W. SMITH, a citizen of the United States, residing at the city of St. Louis, in the State of Missouri, have invented certain new and useful Improvements in Beds, of which the following is a specification.

The object of this invention is so to arrange the door for the closet inclosing a wall-bed or door-bed and so to pivot such a bed thereon as to require the minimum space in the thickness of the wall, and also to take up the minimum space in the room due to the thickness of the door or location of the door when the bed is extended, and also to accord the largest and most convenient space when the bed is extended for access to the interior of the closet.

If in conjunction with the present invention the bed be used that forms the subject-matter of the application for patent of this inventor and William J. Duvall, Serial No. 595,260, the greatest economy in space will be effected, but either invention may be used separately.

In the accompanying drawings forming part of this specification, in which like numbers of reference denote like parts wherever they occur,

Figure 1 is a front elevation with the doors closed;

Figure 2 is a vertical sectional view showing one of the doors closed and the other one hinged thereon open, with the bed in position in the closet;

Figure 3 illustrates a detail;

Figure 4 is a top plan view of the doors and bed, the doors being closed and the bed being in the closet;

Figure 5 is a similar view, but with one of the doors open;

Figure 6 is a top plan view showing the doors open and the bed extended; and

Figure 7 is similar to Figure 4, but shows a larger closet and wider doors and a bed the width of which is about equal to that of one of the doors, instead of the bed being wider than one of the doors, as shown in Figures 4 and 5.

The alcove or recess 1 may be of any necessary depth or length. In the construction of large apartment buildings, hotels, clubs, and flats space is a desideratum, because the more living quarters that can be worked into a given land area, the more productive is the investment. Vice versa,

the less occupiable space is provided in such a structure, the larger the overhead expense.

By the particular arrangement of the doors 2 and 3 of this invention and the pivoting at 4 and 5 of door 2, great economy in space is accomplished by lessening the arc of travel of the bed 6 and the complete closure for the alcove 1.

As is shown in the drawings, there must be either one door that extends entirely across the opening into alcove 1 or a plurality of doors, e. g., doors 2 and 3 attached together by hinges 7. Otherwise stated, and assuming the bed 6 to be attached to the closure for the alcove 1 (as it is in all such constructions), the depth necessary for clearance of the rear corner 8 of the folded bed must be greater if the pivoting of the said closure be at approximately its middle than if it be off to one side. The particular rear corner that must thus clear is the one on the side opposite to the side of initial motion.

Furthermore, if the closure be one door extending clear across the opening into alcove 1, the arc of travel described by its outer moving edge will be twice as large in the room as it will be if the said closure is bifurcated and its members hinged together, as shown in the drawings.

It will, of course, be understood that it is immaterial whether the rear corner 8 that must clear is the lefthand or the righthand corner, but in the drawings from the standpoint of the observer the corner 8 is the rear lefthand corner.

In use door 3 will be of relatively less importance and merely for the purpose of hiding the closet part of alcove 1, where the clothes hooks 9 and the like are located. There is material economy of space in building construction and also material diminution in the waste of occupiable space where a clothes closet or the like can be combined with the alcove for a door-bed or the like, because at least one partition or similar wall will be omitted and its space saved and its costs of construction likewise avoided.

The bed 6 may be attached to the pivoted door in any desired manner, door 3 being, so to speak, only an idler. The said idler door 3 will preferably fold back on hinge or hinges 7, either as shown in Figure 5 or Figure 6, and may lap as a leaf in either direction.

The pivot points 4 and 5 may be in the center of door 2 where the closure for alcove 1 is divided into two or more parts with an idler or idlers 3, and need not necessarily 5 be in the center of door 2 or its equivalent part. It may be eccentric with relation thereto. It is evident, however, that locating the pivotal points 4 and 5 in the center of door 2 or equivalent part will form an 10 eccentric pivoting of the bed-bearing member relative to the cross area or dimension of the bed 6 and also relative to the cross dimension of the alcove or closet 1.

Particular consideration of the drawings, 15 for instance Figure 4, will make it plain that if the member bearing the bed 6 were pivoted at a point vertically in the same plane as the hinges 7, swinging the bed 6 on such pivotal point would cause corner 20 8 to strike the rear wall 10. Such construction necessitates much greater depth to the alcove 1. By locating the pivotal points 4 and 5 well to one side of the center line of the bed 6, the corner 8 begins to move 25 forward toward the exit from the alcove 1 practically as soon as the bed 6 is rotated in the slightest degree upon the said pivots.

In locating the pivotal points 4 and 5, care must be observed not to get them so 30 far to one side that the weight of the bed 6 will cause the same to sag, as this is objectional, because it puts a strain upon the bed 6 and upon the door 2, and may be of such a degree that the bed 6 will touch the 35 floor and prevent easy movement. Approximately one-fourth of the distance from the side of the bed 6 forms a practical point for the location of the pivots 4 and 5.

The guards 11 protect the corners of the plastering from chipping or breaking. 40

As clearly shown in Figures 2, 3, 4, 5, 6, and 7, the pivotal points 4 and 5 are located forward of the center line of the door 2, by reason of which the front corner of that side or edge of door 2 that adjoins 45 guard 11 clears instantly upon the first beginning of rotation of the bed-bearing member 2. This feature, in common with others hereinbefore described, lessens the amount of space or room required for 50 installation and operation of this door-bed.

Having thus described this invention, I hereby reserve the benefit of all minor changes in form, arrangement, order or use 55 of parts, as it is evident that many minor changes may be made therein without departing from the spirit of this invention or the scope of the following claim.

I claim:

In a wall bed, in combination, a bed alcove, a door turnable in the opening of the said alcove on vertical pivots lying within the plane of the door and substantially concealed between the top and the bottom edges of the door and the adjacent portions of the alcove, said pivots being centered relative to the vertical edges of the door but eccentrically located with respect to the sides thereof so as to be positioned nearer 65 to one side of the door than to the other, and an article supported on the side of the door which is remote from the pivots. 70

In testimony whereof I hereunto affix my signature.

ALBERT W. SMITH.
